UNITED STATES PATENT OFFICE

91,828

DESIGN FOR A BUILDING

Solis D. Kaplan, Philadelphia, Pa.

Application June 17, 1933, Serial No. 48,436

Term of patent 3½ years

To all whom it may concern:

Be it known that I, SOLIS D. KAPLAN, a citizen of the United States, residing at Philadelphia, in the county of Philadelphia and State of Pennsylvania, have invented a new, original, and ornamental Design for Buildings, of which the following is a specification, reference being had to the accompanying drawing, forming part thereof.

Figure 1 is a perspective view of a building made in accordance with my design;

Fig. 2 is an elevational view of one end thereof; Fig. 3 is an elevational view of the other end thereof; and

Fig. 4 is an elevational view of the front thereof.

I claim:

The ornamental design for a building as shown. In testimony whereof, I have hereunto signed my name.

SOLIS D. KAPLAN.
